IVAR AMUNDSEN, OF OSLO, AND ERIK STEPHANSEN, OF SLEMDAL, NEAR OSLO, NORWAY; SAID STEPHANSEN ASSIGNOR TO SAID AMUNDSEN.

REFRIGERATION PLANT OF THE INTERMITTENT-ABSORPTION TYPE.

Application filed May 9, 1928, Serial No. 276,473, and in Norway February 27, 1928.

This invention relates to refrigeration plants of the absorption type (adsorption type) where the absorption vessel is alternately heated and cooled and where the supply of cooling water to the absorption vessel comes through a siphon tube from a cooling water tank.

The duration of the heating period for the absorption vessel for an apparatus of this kind ought to be shorter when the cooling water temperature is high to get the most economical operation, because by the higher temperature of the cooling water there is less absorbed cooling medium to be driven out.

10 The invention intends to improve the siphon system for the cooling water supply in such a way that the siphon effect is started earlier by a higher temperature of the cooling water than by a lower temperature, the 15 heating arrangement for the absorption vessel being in a known manner controlled by means of the intermittent water supply.

In accordance with the invention, this is obtained by arranging the inlet for the siphon 20 a little above the bottom of a submerged bell which is open at the bottom and the upper closed part of which is connected to an air container placed in the outlet from the heating chamber of the absorption vessel.

25 At the same time the cooling water tank is supplied with an overflow outlet placed somewhat below the highest point of the siphon whereby the level in the water tank can never reach such a height that the 30 siphon effect may start for that reason.

When the heating of the absorption vessel is advanced so far that the air container in the upper outlet is heated, then the air in this container will expand and press the water 35 level downward in the submerged bell which encloses the inlet opening for the siphon until by a certain temperature in the expansion vessel an air bubble will be pressed up in the siphon. This air bubble will rise up 40 in the siphon tube thereby forcing the water over the overflow so that the siphon effect starts.

When the water in the water tank by means 45 of the siphon has been sucked down to a level corresponding to the lower edge of the submerged bell, air will enter into this from the outside thereby renewing the air filling of the bell and at the same time stopping the siphon effect. A new heating period is 50 thereby started.

In the drawing in which the sole figure shows a form of the invention in vertical section, and largely diagrammatic,

1 is the absorption vessel and 2 is the cooling and heating jacket; 3 is the outlet conduit 60 from jacket 2; 4 the cooling water tank and 5 the siphon leading from the cooling water tank 4 to jacket 2.

In the outlet 3 is placed a closed expansion vessel 6 which by means of the tube 7 is connected to the upper part of a submerged bell 8, the lower edge of which is a little below the inlet opening 10 for the siphon 5.

During the heating period the water level 70 rises in the water tank 4 up to the level indicated by the line 11, and is kept constantly on this level; the water which is led to the tank through the water supply tube 13 is running out through the overflow 14. The water level in the siphon 5 is kept on the same level as in 75 the tank, that is to say, somewhat lower than the highest point of the siphon, while the level in the submerged bell, for instance, is at the indicated line 12.

When the heating of the absorption vessel 80 has advanced to the point where the expansion vessel 6 will be heated, the air in this vessel will expand, thereby forcing the water level 12 downwards until it comes below the inlet opening 10 for the siphon. The 85 air which now is going up into the siphon tube 5 forces the water in the siphon over the over-flow whereby the siphon effect is immediately started, at the same time starting the cooling of the absorption vessel and 90 preferably of the expansion vessel so that the water level in the submerged bell will rise.

The siphon effect will continue until the level line 11 reaches below the lower edge 95 of the submerged bell. At this moment the siphon effect is automatically broken off, at the same time new air being led to the interior of the submerged bell.

It will be understood that the starting of 100 the siphon effect in accordance with this invention is not controlled by the level of the water in the cooling water tank 4, this level being constant at the level 11 when once it has reached this level; but the siphon effect 105 is started—and thereby stopping the heating and starting the cooling cycle of the plant—when the absorption vessel is heated through. This is naturally the right point to stop the heating and the time it will be automatically 110

stopped is in every case dependent upon the conditions under which the refrigerating plant is working, such as temperature of the cooling water and in the evaporator and of 5 the duration of the absorption period. The duration of this period will however, be kept constant by regulating the dimension of the outlet orifice in the usual manner.

To obtain a rapid cooling of the expansion 10 vessel by the starting of the siphon effect, it is appropriate as shown on the drawing to lead the siphon tube 5 through or close to the expansion vessel, but this is not absolutely necessary.

15 The arrangement is especially advantageous when used in connection with such refrigerating apparatuses where the absorption vessel is heated by means of steam or other vapour, thereby obtaining a very rapid 20 increase in temperature in the outlet when the temperature in the absorption vessel has increased to such a point that a part of the steam is going up through the outlet 3. But it will of course be understood that the invention 25 is not limited for use in connection with apparatuses with this sort of heating.

What we claim is:

1. In refrigerating apparatus of the type 30 including an absorbing or adsorbing vessel having a heating jacket, means for intermit-

tently supplying cooling water to said absorbing vessel comprising a reservoir, a siphon leading from said reservoir to a discharge point in operative relation to said absorbing vessel, a submerged bell in said reservoir having an open bottom, the inlet end of said siphon terminating within said bell a little above the plane of the open end thereof, a gaseous fluid container arranged in the outlet of said heating jacket said container 40 being in communication with said bell.

2. Apparatus as claimed in claim 1, the cooling water reservoir being supplied with an overflow on a level somewhat below the highest point of the siphon so that the starting of the siphon cannot be incited by the water level in said reservoir, but is controlled solely through the expansion of the gaseous fluid in said container, said fluid expanding when the container is heated thereby pressing 45 a bubble from the submerged bell up into the siphon, whereby the siphon effect is started.

3. Apparatus as claimed in claim 1 the siphon being placed in such relation to the container, that the water coming through the 50 siphon directly cools said container.

In testimony whereof we have signed our names to this specification.

IVAR AMUNDSEN.

ERIK STEPHANSEN.
